CLAIM

The ornamental design for the refrigerator cabinet door lock as shown and described.

DESCRIPTION

FIG. 1 is a perspective view of a refrigerator cabinet door lock;

FIG. 2 is an enlarged perspective thereof;

FIG. 3 is a front view thereof;

FIG. 4 is a back view thereof;

FIG. 5 is a left side view thereof;

FIG. 6 is a top view thereof;

FIG. 7 is a bottom view thereof;

FIG. 8 is an enlarged perspective of another embodiment of a refrigerator cabinet door lock;

FIG. 9 is a front view thereof;

FIG. 10 is a back view thereof;

FIG. 11 is a right side view thereof;

FIG. 12 is a top view thereof; and,

FIG. 13 is a bottom view thereof.

The right side view forms no part of the embodiments of the claimed design shown in FIGS. 1-7.

The left side view forms no part of the embodiments of the claimed design shown in FIGS. 8-13.

Elements shown in broken line form no part of the claimed design.
